US0D1000313S

(12) **United States Design Patent** (10) Patent No.: **US D1,000,313 S**
(45) Date of Patent: ** Oct. 3, 2023

(54) **HYDROPONIC SYSTEM**

(71) Applicant: **OMS Investments, Inc.**, Los Angeles, CA (US)

(72) Inventors: **Joseph Craig**, Marysville, OH (US); **Bradley Schultz**, Powell, OH (US); **Angie Gray**, Marysville, OH (US); **Whitney Maiden**, Marysville, OH (US); **Ryan Berger**, Columbus, OH (US); **Sean Montag**, Columbus, OH (US)

(73) Assignee: **OMS Investments, Inc.**, Los Angeles, CA (US)

(**) Term: **15 Years**

(21) Appl. No.: **29/801,910**

(22) Filed: **Aug. 2, 2021**

Related U.S. Application Data

(62) Division of application No. 29/755,189, filed on Oct. 19, 2020, now Pat. No. Des. 926,627, which is a division of application No. 29/670,949, filed on Nov. 21, 2018, now Pat. No. Des. 899,299.

(57) **CLAIM**

The ornamental design for a hydroponic system, as shown and described.

DESCRIPTION

FIG. 1 is a top isometric view of a hydroponic system illustrating the new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top planar view thereof;

FIG. 7 is a bottom planar view thereof; and,

FIG. 8 is a bottom isometric view thereof.

The broken lines in the drawings are included for the purpose of illustrating portions of the hydroponic system that form no part of the claimed design.

1 Claim, 8 Drawing Sheets
